COMPRESSED AIR ECONOMIZER FOR FLUIDIC CONTROLS

George Napoleon Levesque, Warwick, R.I., assignor to Brown & Sharpe Manufacturing Company, North Kingstown, R.I., a corporation of Rhode Island

Filed Dec. 15, 1966, Ser. No. 601,897

6 Claims. (Cl. 230—1)

ABSTRACT OF THE DISCLOSURE

The disclosure of the present invention comprises a plurality of fluidic control elements having inlet and discharge apertures thereto, a gas confining enclosure within which said fluidic control elements are housed including said discharge apertures, a low pressure gaseous fluid pump connected between the enclosure and said fluidic control elements providing a circuit to withdraw from said disclosure and to supply a filtered compressed gaseous fluid to said fluidic control elements at a predetermined fluidic element operating pressure, and means for supplying additional filtered compressed gaseous fluid to said circuit to maintain a fluid pressure in said enclosure slightly above atmosphere.

In one form of the invention additional filtered compressed gaseous fluid is supplied directly to the enclosure from an outside source at slightly above atmospheric pressure.

In another form of the invention additional filtered compressed gaseous fluid is supplied to said fluidic control elements at said operating pressure, and a restricted outlet is provided from said enclosure for exhausting filtered gaseous fluid therefrom at slightly above atmospheric pressure.

The present application relates to a compressed air economizer for fluidic controls.

A conventional fluidic control system of the general type herein referred to for use in an automatic machine tool may be of the wall attachment type comprising, by way of example, one hundred or more or-nor and flip-flop gates each operated by compressed air supplied at a low operating pressure which is normally held below 15 p.s.i. The compressed air for operating the several fluidic devices is conveniently supplied from a shop compressed air line which may be regulated to about 90 p.s.i. For use in a fluidic control panel the compressed air from the shop line is filtered to eliminate water and oil, and is passed through a reducing valve in order to reduce the air pressure entering the fluidic control panel to the desired low pressure in the order of 15 p.s.i.

While the amount of air required by any single or-nor or flip-flop gate is relatively small, amounting to about 17 standard cubic feet per minute (17 s.c.f.m.) it will be appreciated that a fluidic system employing 100 such devices will, if all of the filtered air is lost, consume about 17 s.c.f.m. requiring a compressor having a capacity of several horsepower of the 90 p.s.i. compressor capacity.

It is a principal object of the invention to provide a fluidic control system of the general type above described having an improved compressed air supply system which will operate with increased efficiency and with a substantially lower consumption of compressed air than is normally required by such systems now in use.

With the above and other objects in view as may hereinafter appear a feature of the invention consists in the provision of a fluidic control circuit which is mounted within a relatively tight enclosure from which a pump takes air and raises the pressure of said air to an amount

2

(3-15 p.s.i.g.) suitable for operating the several elements of the control circuit, additional filtered air being supplied to the enclosure to make up for lost air and to maintain within the enclosure a slightly above atmospheric pressure to exclude outside contaminated air.

The several features of the invention consist also in the devices, combinations and arrangements of parts herein after described and claimed which together with the advantages to be obtained thereby will be readily understood by one skilled in the art from the following description taken in connection with the accompanying drawings in which:

FIG. 1 is a perspective view of a fluidic control panel mounted within a substantially air tight enclosure to which compressed air is supplied which is filtered and regulated to slightly above atmospheric pressure and an air pump by means of which filtered air from the enclosure is raised to a suitable operating pressure in the order of 3 to 15 p.s.i.g. to the several devices within the panel at the desired operating pressure, a portion of the enclosure being broken away to show underlying parts including a flip-flop and an or-nor gate connected to operate a pilot valve and a reversible piston; and

FIG. 2 is a somewhat fragmentary perspective view of the fluidic control panel shown in FIG. 1 modified to include an air motor and an air pump connected to withdraw filtered air from the enclosure and to add such additional filtered air as may be required from supply at the desired operating pressure to the several devices within the panel, and a pressure control air outlet from said enclosure.

Referring specifically to the drawings, the invention is illustrated as embodied in a fluidic control system suitable for controlling a machine tool. It is contemplated that a fluidic control system of the general type referred to may have as many as 100 or-nor and flip-flop gates, which are utilized to control the automatic operation of the machine. FIG. 1 illustrates one example of a bi-stable flip-flop gate and a companion mono-stable or-nor gate coupled to control the operation of a suitable pilot valve which directs the flow of a 90 p.s.i. compressed air line into one of two alternative channels to determine the direction of movement of a hydraulic piston. It will be understood that this control sequence is illustrated as an example of the many such controls which may be found in a complex fluidic control system suitable for controlling the operation of a machine tool. The illustrated panel may be built up of a plurality of separated layers having etched therein a substantial number of such or-nor and flip-flop gates.

In the embodiment of FIG. 1 there is provided a fluidic block or panel 10 made up in the usual manner of successive layers of a suitable glass or similar material, which are cemented together, said layers, not specifically shown, having etched therein the desired arrangement of gates, resistors and connecting passageways. In the illustrated embodiments of the invention the panel 10 is mounted in an enclosure 12 which is broken away to disclose the underlying panel 10. Two wall attachment devices are shown in dotted lines in the panel 10 including a bi-stable flip-flop gate 14 and a mono-stable or-nor gate 16, which are connected in a control sequence with a fluidic gate controlled pilot valve 18 to determine the direction of drive of a piston 20. The flip-flop gate 14 of FIG. 1 comprises a main passageway 22 which is connected with an inlet-supply line 23, and is formed with two forks 24, 26, two control jet passageways 28, 30 opening into the base of the forks at opposite sides thereof, and vents 32, 34 for the control jets. The fork 26 of the flip-flop gate is connected by a pipe 36 with one of two control inlet passageways 37 of the or-nor gate 16 which is similarly formed with a main passage

way 38 connected with the inlet supply line 23 and having two forks 40, 42 the two control inlet jet passageways 37 entering from the left side of the gate as shown, an exhaust connection 43 for the control jets 37 and an additional small exhaust connection in each fork.

The or-nor gate 16, which is mono-stable, has a normal bias to the left, so that the operating pressure introduced through the main passageway 38 is normally directed into the fork 40. However, when operating pressure is directed through pipe 36 and the control inlet passageway 37 the operating pressure from the main passageway 38 is diverted into the fork 42.

The control jet passageways 28, 30 of the flip-flop gate 14 are fed from the supply line 23 through resistors 29, 31 which supply a control pressure to said control jet passages in the order of 1.5 p.s.i. The flip-flop gate 14 is actuated by means of two push buttons designated at Rt. and Lt. respectively. The Rt. push button when pressed closes the open upper end of the control jet passageway 30 causing the 1.5 p.s.i. control pressure therein to be directed against the operating pressure which is diverted into the left hand fork 24. In the illustration shown this pressure is vented to exhaust. Pressing the Lt. push button closes the open end of an upward extension of control passageway 28 causing a control pressure of 1.5 p.s.i. to be directed against the stream of operating pressure from the left diverting same into the right hand fork 26, and thence through the pipe 36 to the connected control inlet passageway 37 of the or-nor gate 16 which causes the operating air pressure through the main channel to be diverted into the right hand fork 42.

By way of example the flip-flop gate 14 and or-nor gate 16 are connected to a fluid logic power amplifier which is the pilot valve above referred to. The pilot valve 18 comprises a housing within which is mounted a valve body 56 rotatably supported in a cylindrical aperture, and a piston 58 having its axis disposed at right angles to that of the valve body 56. The piston, mounted in a cylinder 59, is grooved to engage an upward extension of the valve body 56, so that an axial shift of the piston will rock the valve body 56 from one to an alternative operative position. A 90 p.s.i.g. compressed air supply line 60 introduced along the axis of the valve body 56 is delivered through a radial conduit therein to one of the two alternative pressure outlets 62, 64 from the valve, acting through suitable connections to drive the piston 20 mounted in a cylinder 68 alternatively in opposite directions. The air pressure from the exhaust end of the cylinder 68 is exhausted to atmosphere through exhaust ports in the housing of pilot valve 18. It will be noted that the filtered compressed air supplied through forks 40 and 42 to the pilot valve 18 is eventually discharged into the enclosure 12 and is thus conserved for reuse. Specifically, when filtered compressed air is supplied through fork 40 to the cylinder 59 to move the pilot valve body to the right, filtered air previously supplied to the right hand end of the piston 58 is exhausted through fork 42 and the exhaust connection therein into the enclosure. Alternatively when operating pressure is applied through the fork 42 to move the pilot valve body to the left filtered air is exhausted from the left hand end of the piston assembly through fork 40 and its associated exhaust connection into the enclosure 12.

Under normal operating conditions in which the various exhaust openings in the panel for both operating pressure and control pressure connections are vented to atmosphere there is a substantial loss of filtered air which as above noted amounts to approximately (.17 s.c.f.m.) .17 standard cubic feet per minute for each of the fluidic devices contained in the panel.

In accordance with the invention provision is made for conserving and for recirculating as large a percentage as possible of the filtered air supplied to the panel with the result that an approximate 75% of the filtered air passing through the several fluidic devices is saved and

recirculated as needed. To this end the fluidic control system, comprising the control panel 10 and the enclosed or-nor and flip-flop elements, is confined within the enclosure 12, which is maintained at slightly above atmospheric pressure to prevent contamination of the filtered air contained in said fluidic system, and a large percentage of this filtered air is collected and recirculated, thus reducing the amount of such air used by the system by as much as 75%.

In the embodiment of the invention shown in FIG. 1 the enclosure 12 is made substantially air-tight. Compressed air is supplied from the conventional 90 p.s.i.g. shop line 60 to a conventional filter 72 which filters and dries the air, then passes through a pressure regulator 74 which is set to provide filtered air through a pipe 76 to the enclosure 12 at a pressure of .072 p.s.i. above atmosphere. Filtered air at a pressure of about 15 p.s.i. is supplied to the several fluidic devices within the panel through line 23 by means of an air pump 78 driven by an electric motor 80, which air pump draws filtered exhaust air from the enclosure 12 through a conduit 82, raises the pressure of said air to the required level of about 15 p.s.i. and directs said recompressed air to the several fluidic devices through the inlet pipe 23. While some of the filtered air supplied to the fluidic devices is lost, as for example, the control pressure supplied to the Lt. and Rt. push buttons above described, which are located outside the enclosure 12, it will be appreciated that the major portion of the compressed air employed to operate the flip-flop and or-nor gates is vented within the enclosure 12 and is subsequently returned to the air pump 78 where it is compressed to the required 15 p.s.i. and returned to the panel 10 through supply pipe 23.

FIG. 2 illustrate an alternative arrangement of the fluidic element control panel, including means for supplying filtered air at the desired operating pressure to the fluidic elements contained within said panel, and enclosure 12 for said panel, means for drawing off and recirculating filtered air vented from said fluidic elements into the enclosure, and a vent 83 through the enclosure for venting a small amount of said filtered air to atmosphere, the vent to atmosphere being gauged to maintain a small internal pressure in the order of 2 inches of water or .072 p.s.i. within the enclosure.

In the disclosure of FIG. 2 compressed air from a shop line, which may, for example, be 90 p.s.i.g. is passed through a variable throttle valve 84, through the filter 72 to an air motor 86 which drives an air recirculating pump 88 which draws filtered air from the enclosure 12 and feeds it to the operating pressure supply line 23 of the panel unit. Air from the exhaust side of air motor 86 is combined with the air from the output side of the air pump 88 to supply the operating pressure supply line 23. In this form of the invention the amount of filtered air which can be captured and recirculated is reduced by the amount of any filtered air loss through push buttons such as those above described and other controls using compressed air which are necessarily located outside the enclosure 81, and additionally the filtered air which is discharged through the vent 83 from the enclosure 12.

The modification shown in FIG. 2 also may be expected to effect substantial savings of the filtered air supplied to the enclosed panel 10. The loss of filtered air is limited to only that amount of such filtered air required by the air motor 86 to drive the air pump 88, in addition to the other relatively small losses above noted. As in the first described embodiment of the invention a saving of filtered air which would ordinarily be lost in the order of 75% may be expected, thereby substantially decreasing the size of compressor required for the 90 p.s.i.g. line by the several horsepower, which would otherwise be necessary for supplying compressed air to the control panel.

While for convenience of illustration the several pump and motor units for supplying filtered compressed air to the fluidic control panel have been illustrated as located

externally of the enclosure 12 it will be understood that these elements may equally well be mounted internally of the enclosure without changing in any way the operation of the apparatus herein described for economizing as to the amount of filtered air used by the apparatus.

It is appreciated that provision has been made in the prior art for supplying filtered air to enclosed areas in which a slightly above atmospheric pressure is maintained to exclude the entry of contaminated air. Such pressurized areas are known as "clean rooms." However, so far as the applicant is aware the filtered air supplied to a "clean room" has not been further pressurized to do useful work, as is the case with applicant's enclosed fluidic control panel.

It will be understood that the invention in its broader aspects is not limited to the two embodiments shown, and that the invention may take other forms within the scope and spirit of the appended claims.

The invention having been described, what is claimed is:

1. Compressed gaseous fluid economizer for a fluidic control circuit having, in combination with a plurality of fluidic control elements having inlet and discharge apertures thereto,

a gas confining enclosure within which said fluidic control elements are housed including said discharge apertures,

a low pressure gaseous fluid pump connected between the enclosure and said fluidic elements providing a circuit to withdraw from said enclosure and to supply a filtered compressed gaseous fluid to said fluidic control elements at a predetermined fluidic element operating gaseous pressure, and

means for supplying additional filtered compressed gaseous fluid to said circuit to maintain a fluid pressure in said enclosure slightly above atmosphere.

15

20

25

30

35

2. The combination of Claim 1, in which the compressed gaseous fluid is compressed air.

3. The combination of claim 2, in which said means for supplying additional filtered compressed air to said circuit comprises a source of high pressure compressed air, and an air filter, and a regulating valve connecting said source of high pressure compressed air into said circuit.

4. The combination of claim 3, in which the air filter and regulating valve are connected between the source of high pressure compressed air and said enclosure for supplying filtered compressed air to said enclosure at slightly above atmospheric pressure.

5. The combination of claim 3, in which a vent is provided from said enclosure sized to exhaust air therefrom at slightly above atmospheric pressure, and said filter and regulating valve are connected with the output side of said pump to supply added filtered compressed air into said circuit at said operating pressure.

6. The combination of claim 5, in which an air motor is connected to drive said pump, and the filtered and regulated compressed air from said source of high pressure compressed air is first applied to drive said air motor, and is then mixed with the output from said pump to supply filtered compressed air to said fluidic elements at said fluidic element operating pressure.
